Primary Examiner — Kelley Donnelly(74) *Attorney, Agent, or Firm* — Benesch Friedlander Coplan & Aronoff LLP**CLAIM**

What is claimed is the ornamental design for a pantry shelf, as shown and described.

DESCRIPTION

FIG. 1 is a perspective view of a pantry shelf showing a new design;

FIG. 2 is a front view of the pantry shelf of FIG. 1;

FIG. 3 is a side view of the pantry shelf of FIG. 1;

FIG. 4 is a cross-sectional view taken along line 4-4 of FIG. 3;

FIG. 5 is a top view of the pantry shelf of FIG. 1;

FIG. 6 is a bottom side view of the pantry shelf of FIG. 1;

FIG. 7 is a perspective view of another embodiment of the pantry shelf of FIG. 1; and,

FIG. 8 is a cross-sectional view taken along line 8-8 of FIG. 7. The components of the display shown in broken lines illustrate portions of the pantry shelf form no part of the claimed design.
